SAFETY DEVICE FOR SEWING MACHINES

Welbie L. Ibbott, Belleville, N. J., assignor to The Singer Manufacturing Company, Elizabeth, N. J., a corporation of New Jersey

Application March 11, 1942, Serial No. 434,157

9 Claims. (Cl. 112—67)

This invention relates to buttonhole sewing machines more particularly of the type disclosed in the U. S. Patent to E. B. Allen, No. 743,213, of Nov. 3, 1903, having a vertically movable knife-bar which carries a buttonhole-cutting-knife and is given an endwise reciprocatory impulse by the action of the stop-motion mechanism of the machine at the close of a buttonhole sewing period to cut the buttonhole slit.

The knife-bar is commonly mounted along side the needle-bar in the head of the machine at the free end of the overhanging bracket-arm, and is connected by mechanism with the stop-plunger such that the downward, or work-severing, stroke of the knife-bar is positive and the upward, or retracting, stroke of the knife-bar is effected through the use of springs. In practice, it has been found that occasionally the buttonhole-cutting-knife is accidentally detained in its lowered position as the result of the work being jammed between the sides of the buttonhole-cutting-knife and the knife-slit in the usual lower work-supporting plate, which jamming is caused by the insecure clamping of the work in stretched condition or the use of a dull knife. When the buttonhole-cutting-knife is not returned to its normal inoperative position at the end of the buttonhole-producing cycle, the work in the work-clamp cannot be removed from the machine. Inexperienced or careless operators, when confronted with this condition, attempt to release the jammed buttonhole-cutting-knife by depressing the starting treadle. When this is done power is applied to the main-shaft and the machine in starting is damaged by the collision of the work-clamp with the buttonhole knife-holder.

The primary object of the present invention is the provision of simple means effective to prevent the starting of the machine when the buttonhole-cutting-knife is held out of its normal retracted position.

A further object of the present invention is the provision of a safety device of the above described character which is in the form of an attachment adapted to be conveniently applied to existing buttonhole sewing machines without necessitating material alterations of the machine.

With the above and other objects in view, as will hereinafter appear, the invention comprises the devices, combinations and arrangements of parts hereinafter described in connection with the accompanying drawings which illustrate a

preferred embodiment of the invention, and in which:

Fig. 1 is a side elevational view of a buttonhole sewing machine embodying the invention.

Fig. 2 represents a fragmentary horizontal sectional view taken substantially along the line 2—2, Fig. 1.

Fig. 3 is a fragmentary side elevational view of the sewing machine, showing the position of the component elements of the buttonhole cutter actuating mechanism when the cutter is at the lower end of its work-severing stroke, and the position of the safety device in its operative or guarding position.

Fig. 4 represents a fragmentary vertical sectional view taken substantially along the line 4—4, Fig. 1, illustrating the position of the stop-cam and the stop-plunger when the buttonhole cutter actuating mechanism is in the position shown in Fig. 3.

Fig. 5 is a perspective view of the safety element showing its preferred shape.

In the particular embodiment of the invention chosen for the purpose of the present disclosure, the machine is constructed with a frame having a bed 1 from which rises a standard 2 of the gooseneck including an overhanging arm 3 terminating in a head 4. The sewing machine illustrated has substantially the same constructive features as are embodied in the straight-buttonhole sewing machine disclosed in the Allen Patent No. 743,213, of Nov. 3, 1903. Such a machine has the usual stitch-forming mechanism including a needle 5 and a complemental loop-taker 6, the period of operation of which is controlled by the usual stop-motion device including a tilting stop-motion lever 7 which is pivoted on trunnion-screws 8 to a frame-bracket 9 secured to the standard 2. The stop-motion lever 7 has journaled therein an upwardly spring-influenced stop-plunger 10 which, when the stop-lever 7 is shifted to stopping position, Fig. 1, is first depressed by the eccentric plunger-depressing portion 11 of a stop-cam 12 connected, as shown in the Allen et al. Patent No. 1,915,910, of June 27, 1933, through speed-reduction gearing 13, 14 to the usual belt-driven main- or arm-shaft 15 and then projected by the spring 16 as the stop-notch 17 in the cam 12 comes into register with the stop-plunger 10.

To provide for swinging the stop-motion lever 7 out of vertical stopping position to start the buttonhole stitching cycle, the stop-motion lever is provided with a forwardly extending arm 18 from the free end of which depends a treadle-

operated rod 19 having in its side a notch 20 adapted to receive a spring-biased latch-lever 21. The latch-lever 21 is fulcrumed at 22 to the under side of the bed 1 and carries an adjustable tripping point 23 which is engaged by a tripping point (not shown) secured on the usual feed-wheel 24 to stop the sewing mechanism at the end of a buttonhole sewing operation. The feed-wheel 24 is secured on the lower end of a vertical feed-shaft 25, which feed-shaft is given one revolution per buttonhole-producing cycle through the usual gear-train connections 26 actuated by the arm-shaft 15. The work-clamp, indicated as 27, is connected to the feed-wheel 24 so as to be shifted relative to the stitching mechanism to assist in producing the buttonhole.

The buttonhole cutting mechanism comprises a vertically reciprocating knife 28 fixed to a knife-holder 29 carried at the lower end of a cutter-bar 30 journaled for endwise reciprocation in the head 4 and connected by a link 31 to the forward end of a cutter-lever 32 fulcrumed at 33 to the arm 8 and biased by a spring 34 to raise the cutter-bar. The rear end of the cutter-lever 32 carries a screw-pin 35 which extends laterally through a vertical slot 36 in a link 37 pivoted at 38 to the front end of a lever 39. The lever 39 is fulcrumed intermediate its ends at 40 to the standard 2 and is formed at its rear end with a slot 41 entered by a lateral stud 42 fixed to the stop-plunger 10. Pivoted at 43 on the link 37 is a latch-lever 44 formed at its upper end with a shoulder 45 which is normally held by a spring 46 in the position shown in Fig. 3, in engagement with and below the screw-pin 35, to couple the lever 39 to the lever 32. When in the position shown in Fig. 3, the latch-lever 44 completes the train of actuating connections between the stop-plunger 10 and the cutter-bar 30 and, in effect, provides a positive drive between the stop-cam 12 and the buttonhole-cutting-knife so that the latter is positively actuated to sever the work when the stop-plunger is depressed by the stop-cam 12.

It will be understood that the work-clamp 27 is shifted relative to the needle to assist in effecting the production of the buttonhole. To prevent accidental operation of the buttonhole cutting mechanism when the work-clamp is positioned beneath the buttonhole-cutting-knife 28 and thereby cause damage to the knife, means substantially the same as that disclosed in the Corrall, et al., Patent No. 1,936,381, Nov. 21, 1933, is provided to uncouple the latch-lever 44 from beneath the screw-pin 35, thus rendering the actuating mechanism for the buttonhole-cutting-knife inoperative. To this end, the latch-lever 44 is preferably formed with a lateral arm 47 which at times rests upon an upturned end-extension 48 of a trip-lever 49 fulcrumed at 50 to the underside of a horizontal lug 51 on the standard 2. The trip-lever carries a follower 52 which is yieldingly maintained in the path of a cam 53 on the feed-shaft 25 by a coil-spring 54.

When the machine is at rest, the parts are in the positions shown in Fig. 1, with the latch-arm 44 resting upon the trip-lever extension 48 and the cutter-lever 32 uncoupled from its actuating lever 39.

When the stop-motion lever 7 is tilted to start the machine, the stop-plunger 10 is tilted out of the stop-notch 17 in the stop-cam 12 and rises slightly under the influence of the spring 46. This slight rise of the stop-plunger 10 swings

the front end of the lever 39 downwardly and lowers the latch-lever 44 so that its shoulder 45, when the latch-lever is later released, may engage under the screw-pin 35 on the cutter-lever 32. As the sewing begins, the cam 53 is given a slow motion in the direction of the arrow, Fig. 2, and when the sewing of the buttonhole is nearing completion, the cam 53 engages the follower 52 and swings the trip-lever 49 sufficiently to remove the extension 48 from under the arm 47 of the latch-lever 44, whereupon the latch 44 is drawn over by the spring 46 so that its shoulder 45 engages under the screw-pin 35 and couples the lever 32 to the lever 39. This cam 53 passes the follower 52 and releases the trip-lever 49 which is then swung by its spring 54 so that its extension 48 bears against the side of the lateral arm 47.

When the sewing operation is completed, the depression of the stop-plunger 10 by the eccentric portion 14 of the stop-cam 12 causes the levers 39 and 32 to move to their positions shown in Fig. 3, as the buttonhole-cutting-impulse is imparted to the knife 28. This impulse raises the lateral arm 47 of the latch-lever above the trip-arm-extension 48 which promptly moves under the same. On the recovery motion of the parts, the lateral arm 47 strikes downwardly upon the trip-arm-extension 48 and effects an uncoupling of the lever 39 from the lever 32 as the cutter-bar 30 is moving upwardly and before the cutter-bar reached the upper limit of its movement.

It will be understood from the above that during substantially the entire buttonhole-producing-cycle the levers 32 and 39 of the buttonhole actuating mechanism are uncoupled and that for only a short period of time at the end of the cycle the said levers are coupled together. Operation of the buttonhole cutting mechanism is thereby prevented during the time that the work-clamp is positioned beneath the buttonhole knife 28.

In practice, it has been found that when the knife becomes dull or when a material having a considerable amount of stretch is being buttonholed, the work occasionally is not cut cleanly by the knife and is pulled into the knife-slot provided in the lower work-supporting plate, thereby wedging the knife in the slot and preventing the springs 46 and 34 from raising the knife upwardly into retracted position. When this occurs the machine stops at the end of the buttonhole-stitching-cycle with the buttonhole-cutting-knife in the work. Obviously, with the knife in this abnormal position, the work cannot be removed from the work-clamp. In the event an inexperienced or careless operator releases the stop-motion mechanism to apply power to the machine in an attempt to elevate the buttonhole-cutting-knife, the work-clamp 27 is shifted relative to the needle and collides with the knife-holder 29 which, of course, has not been elevated by the application of power to the machine.

To prevent the release of the stop-motion mechanism to start the machine when the buttonhole-cutting-knife 28 is held in the work, there is provided a safety device connected to be operated by the actuating connections between the stop-plunger 10 and the buttonhole knife-bar 30. As clearly shown in Figs. 1 and 5, the safety device comprises an attachment in the form of a lever 55 adapted to be fulcrumed intermediate its ends upon the existing shoulder-screw 56 with which the machine is equipped. The forward end of the safety lever 55 is pref-

erably formed with an open ended slot 57 providing a bifurcated extremity adapted to straddle the reduced cylindrical portion of a nut 58 (Fig. 2) adapted for locking the screw-pin 35 in the cutter-lever 32. The rear-end of the safety lever 55 is inclined, as at 59, and is adapted to be swung into the path of movement of the upper end of the stop-motion-lever 7 when the component parts of the buttonhole cutting mechanism are in the positions illustrated in Fig. 3.

The operation of the safety lever 55 is as follows: When the stop-plunger 10 is positioned at its upper limit, which is the case when the machine is at rest (Fig. 1), or when the machine is traveling through all but the last portion of the buttonhole-producing-cycle, the safety lever 55 is positioned so that its inner end 59 is located at a level above the upper end of the stop-motion-lever 7. When the stop-motion lever 7 is released to swing into its vertical stop-position and the stop-plunger 10 is depressed by the eccentric portion 11 of the stop-cam 12, the screw-pin 35 carried by the cutter-lever 32 is raised upwardly by the latch 44, link 37 and lever 39. In its movement upwardly, the screw-pin 35 swings the safety lever 55 about its fulcrum-stud 56 in such a way as to lower the inner end 59 of the safety lever 55 into the path of movement of the stop-motion lever. When the safety lever is in this position, the stop-motion lever cannot be swung out of its vertical stop-position. In other words, the machine cannot be started. Having this in mind, it will be understood that should the buttonhole-cutting-knife 28 be held in its lowered work-severing position, the parts will be maintained in the position shown in Fig. 3, in which case the safety lever 55 will prevent the manual swinging of the stop-motion-lever 7 out of its vertical stopping position to start the machine.

From the above description, it will be understood that a simple and effective means has been devised which will preclude the starting of the machine during the time that the buttonhole-cutting-knife is in a position such that the work-clamp will collide with the knife-holder and damage the machine. It will be appreciated also that the safety device in question is in the form of an attachment which can be readily applied to existing machines by providing a nut 58 having a reduced cylindrical portion and a slightly longer shoulder-screw 56.

While I have illustrated and described the preferred form of construction for carrying my invention into effect, this is capable of variation and modification, without departing from the spirit of the invention. I therefore do not wish to be limited to the precise details of construction set forth, but desire to avail myself of such variation and modifications as come within the scope of the appended claims.

Having thus set forth the nature of the invention what I claim herein is:

1. A group-stitch sewing machine having stitching devices, a work-clamp, a work-cutting knife normally in retracted position during the stitching operation, a stop-motion device including a notched cam, a movable stop-motion lever having a running position and a stop-position and a stop-plunger carried by said lever and adapted to enter the notch in said cam to stop the machine, mechanism operatively connecting said work-cutting knife to said stop-plunger, and an element directly connected to said mechanism to move into the path of said stop-motion lever for preventing movement of the latter into its

running position when said work-cutting knife is out of its normally retracted position.

2. A group-stitch sewing machine having stitching devices, a work-clamp, a work-cutting knife normally in elevated position during the stitching operation, a stop-motion device including a notched cam, a movable stop-motion lever having a running position and a stop position and a stop-plunger carried by said lever and adapted to enter the notch in said cam to stop the machine, mechanism operatively connecting said work-cutting knife to said stop-plunger, and a pivotal member connected directly to one of the component elements of said mechanism and operated thereby to move into the path of said stop-motion lever and prevent movement of the same into its running position when said work-cutting knife is below its normal or elevated position.

3. A group-stitch sewing machine having stitching devices, a work-clamp, a work-cutting knife normally in elevated position during the stitching operation, a stop-motion device including a notched cam, a movable stop-motion lever having a running position and a stop position, and a stop-plunger carried by said lever and adapted to enter the notch in said cam to stop the machine, mechanism operatively connecting said work-cutting knife to said stop-plunger, and a single pivotally supported lever connected at one end to one of the component elements of said mechanism and operated thereby so that the other end of the lever moves into the path of said stop-motion lever and prevent movement of the same into its running position when said work-cutting knife is below its normal or elevated position.

4. A group-stitch sewing machine having in combination, a frame including a bracket-arm terminating in a head, complementary stitching instrumentalities, a work-clamp, a work-cutting knife normally in elevated position during the stitching operation, a bar journaled in said head and carrying said knife, a stop-motion device including a notched cam, a tilting stop-motion lever having a running position and a stop position, and a stop-plunger carried by said lever and adapted to enter the notch in said cam to stop the machine, mechanism operatively connecting said work-cutting knife to said stop-plunger, said mechanism including a cutter-lever connected by a link to said knife-bar, and a member directly connected to said cutter-lever and operated thereby to move into the path of said stop-motion lever for preventing movement of the latter into its running position when said work-cutting knife is out of its normal or elevated position.

5. In a sewing machine of the buttonhole making type having a main-shaft, sewing and work-clamping devices driven by said main-shaft, a stop-motion device including a manually shiftable starting element applied to said machine to control the period of operation of said main-shaft, and a work-cutting knife at rest during the sewing operation with mechanism to operate it automatically; the provision of a single lever-member of the first order having one of its ends bifurcated to embrace one of the component elements of the knife-operating mechanism and so positioned that its other end will block movement of said starting element to running position when said knife is moved out of its "at rest" position.

6. A buttonhole sewing machine having, in combination, a frame including a bracket-arm terminating in a head, a work-cutting knife nor-

normally in elevated position during the stitching operation, a bar journaled in said head and carrying said knife, a stop-motion device having a running position and a stop position adapted to stop the machine in a definite stop position, mechanism operatively connecting said work-cutting knife to said stop-motion device, said mechanism including a pivotally mounted lever, and a member fulcrumed upon said frame and having one of its ends shaped to engage said pivotally mounted lever and be oscillated thereby about its fulcrum so that the other end of said member moves into a position such that it will prevent movement of the stop-motion device into its running position when said work-cutting knife is out of its normal or elevated position.

7. A buttonhole sewing machine having, in combination, a frame including a bracket-arm terminating in a head, a work-cutting knife normally in elevated position during the stitching operation, a bar journaled in said head and carrying said knife, a stop-motion device including a notched cam, a movable stop-motion lever having a running position and a stop position, and a stop-plunger carried by said lever and adapted to enter the notch in said cam to stop the machine, mechanism operatively connecting said work-cutting knife to said stop-plunger, said mechanism including a pivotally mounted cutter-lever provided with a screw-pin, and a member fulcrumed on said frame and slotted at one end to engage said screw-pin and be operated by said cutter lever to move into the path of said stop-motion lever for preventing movement of the latter into its running position when said work-cutting knife is out of its normal or elevated position.

8. A safety device adapted for use on a sewing machine having a work-cutting knife normally in elevated position during the stitching operation, a stop-motion device including a movable stop-motion lever having a running position and a stop position, and mechanism connecting said work-cutting knife for actuation by said stop-motion device, said safety device comprising a lever-member adapted to be pivotally supported for limited oscillatory movements, said lever-member having one of its ends slotted to engage one of the component elements of said mechanism whereby the other end of said lever-member is moved into the path of said stop-motion lever for preventing movement of the latter into its running position when the work-cutting knife is below the normal or elevated position.

9. A safety attachment adapted for use on a sewing machine having a work-cutting knife normally in elevated position during the stitching operation, a stop-motion device including a movable stop-motion lever having a running position and a stop position, and mechanism connecting said work-cutting knife for actuation by said stop-motion device, said safety device comprising a single lever-member of the first order having one of its ends bifurcated to embrace one of the component elements of said mechanism whereby the other end of said lever-member is moved into the path of said stop-motion lever for preventing movement of the latter into its running position when the work-cutting knife is below the normal or elevated position.

WELBIE L. IBBOTT.
